(57) **CLAIM**

The ornamental design for a stroller carabiner clip as shown and described.

DESCRIPTION

FIG. 1 is an angled isometric view of my new design for a stroller carabiner clip;

FIG. 2 is a right side view thereof;

FIG. 3 is a left side view thereof;

FIG. 4 is a front view thereof;

FIG. 5 is a back view thereof;

FIG. 6 is a top-down thereof;

FIG. 7 is a bottom-up view thereof; and,

FIG. 8 is an angled isometric view thereof, with external elements shown for context, that form no part of the claimed design.

With respect to the drawings, the broken lines shown on the article itself represents stitching and forms part of the claim. The broken lines showing the handle of a stroller in FIG. 8 represent environment and form no part of the claim.
